UNITED STATES PATENT OFFICE

2,490,272

PORTABLE SWIMMING POOL

Clifford Kastle, Los Angeles, Calif.

Application May 13, 1946, Serial No. 669,387

6 Claims. (Cl. 4—172)

1

This invention relates to swimming pools, and particularly to a swimming pool construction of a portable nature, since it is easily assembled and dismantled for removal from one location to another with the minimum of effort and time.

Small swimming pools, constructed from waterproof canvas or rubberized material, are known, such pools having the canvas fastened to an upper frame-work and resting either on a floor or on the ground. The present invention is directed to a full sized type of swimming pool which may be used on school playgrounds or for a traveling theatrical troupe. In general, the pool is constructed of sections which may be quickly put together by bolts to provide a water tight tank. The pool may be provided with a deck or a platform and handrails under which may be provided locker room space, if desired. Inasmuch as the bottom of the pool rests on the ground or floor, ladders are provided to enable the swimmers to reach the deck or platform conveniently. The sections are of four types having special configurations and interlocking edges, many of which are interchangeable. They are made of light material, such as aluminum, and may be thus easily handled and transported. Special reinforcing is constructed into each section.

The principal object of the invention, therefore, is to provide an improved swimming pool construction.

Another object of the invention is to provide an improved swimming pool which may be quickly assembled and dismantled and moved from one location to another.

A further object of the invention is to provide an improved portable swimming pool of normal size suitable for schoolgrounds and theatrical performances.

A still further object of the invention is to provide a swimming pool of sections having water tight interlocking joints which may be quickly dismantled and reassembled.

Although the novel features which are believed to be characteristic of this invention will be pointed out with particularity in the appended claims, the manner of its organization and the mode of its operation will be better understood by referring to the following description read in conjunction with the accompanying drawings, forming a part hereof, in which:

Fig. 1 is a plan view of a portable swimming pool embodying the invention.

Fig. 2 is a side elevational view of the swimming pool as shown in Fig. 1.

2

Fig. 3 is a cross-sectional view at one end of the swimming pool.

Fig. 4 is a cross-sectional end view of the swimming pool showing the bracing of the side members.

Figs. 5 and 6 are detail views showing the interlocking arrangement of the side and bottom sections of the pool taken along the lines 5—5 and 6—6, respectively, of Fig. 4.

Fig. 7 is a perspective exploded view showing the manner in which the sections are arranged for assembly.

Fig. 8 is a plan view of the intersection of four bottom sections of the pool.

Figs. 9 and 10 are detailed cross-sectional views showing the manner of interlocking the corners of the bottom sections of the pool and taken along the lines 9—9 and 10—10, respectively, of Fig. 8, and

Fig. 11 is a cross-sectional, detail view of the glass panel at one end of the pool taken along the line 11—11 of Fig. 1.

Referring now to the drawings, in which the same numerals identify like elements, and referring particularly to Figs. 1 and 2, the pool is rectangular in shape and made up of intermediate bottom sections 5 of one type, corner bottom sections 6 of a second type, side and end sections 7 of a third type, and corner side sections 8 of a fourth type. Surrounding the pool are stud supports 10 on which is supported a platform or deck 12 made up of a series of spaced and interlocking strips 13. (See Figs. 3 and 4.) Two ladders 15 and 16 with hand rails 17, provide access to the deck 12, while a hand rail 18 may encircle the entire deck for protection. It is to be understood that locker space, dressing rooms, and shower facilities may be provided under the deck and between the studs 10 by walling therebetween and providing a ceiling 20 and a floor 21 of suitable materials. Steel ladders 3 and 4 may be provided to aid the swimmers in getting out of the pool. These ladders may be hung over the edges of the pool.

In one or more of the side or end sections 7, a sight glass or window, such as shown at 22 in Fig. 11, may be provided, this window being inserted in the sections of the tank with the proper brass and rubber water-tight fittings shown at 23 and 24. Inlet and outlet holes may be provided at 26 and 27, respectively, an additional opening being shown at 28 in Fig. 7 for the purpose of completely draining the tank. Between openings 26 and 27, a circulatory system may be provided for recirculating the water from the

outlet 27 back into the inlet 26 through any suitable filter arrangement.

Referring now to the specific construction of the pool, as mentioned above, it is made up of four different types of sections; that is, bottom, bottom-corner, side, and side-corner sections. Referring now to Fig. 7, two bottom sections are shown at 32 and 33 and two bottom-corner sections are shown at 30 and 31. Although all sections could be made of wood, plastic, and steel, sheet aluminum is preferred, because of its lightness and ease of fabrication. Bottom sections 32 and 33 are flat with upturned ends at right angles to the bottom portions. The corner-bottom sections have upturned ends and sides with rounded corners, as shown at 35, formed by the bottom surface and the upturned portions. The corners may be formed and then welded. Flanges 29 and 38 extend outwardly from the bottom and bottom-corner sections, these flanges being drilled with holes approximately six inches apart to receive the fastening bolts. Referring specifically to corner section 31, it will be noted that the inner edges have a step-back portion 37 which extends completely around the inner edges of the section and up the upturned portions. At the inner corner 40 of section 31, there is a double step-back to form a water-tight joint between the four sections 30, 31, 32, and 33, as shown in Figs. 8, 9, and 10.

Section 30 is similar to corner section 31, except that it has a step-back 41 only on one of the inner edges of the section. Section 32 has a step-back edge 42 similarly to edge 41 of section 30, while section 33 has a step-back end edge 44 and a step-back side 45 with the corner 46 having a double step-back similarly to corner 40. Each of these sections is provided with stiffening ribs, as shown at 47, 48, and 49.

Referring now to Figs. 8, 9, and 10, the sections 30, 31, 32, and 33 are shown interlocked, Fig. 8 being a plan view and Figs. 9 and 10, cross-sectional views taken at right angles at the corner. This interlocking arrangement is important, since it permits a non-leakable pool to be quickly dismantled and re-assembled. To insure a water-tight condition, the adjacent overlapping surfaces of double step-backs 40 and 46 at the corners and along the sides are separated by strips of $\frac{1}{16}$ inch Johns-Manville No. 60 service sheet packing. With this packing between the joints, the sections are then bolted together, preferably with $\frac{1}{4}$ inch bolts 36 spaced approximately six inches between centers. (See Fig. 5.) As mentioned above, it has been found that although wood, plastics, or steel could be used for the sections, sheet aluminum is preferred, the aluminum being treated with Alrok followed by a zinc chlorinate primer and then baked enamel to prevent the aluminum from being affected by the chlorine in the water.

After the bottom sections are bolted together, the side-corner sections, such as 51 and 52, are then bolted to the bottom sections 30 and 31, respectively, these sections having the curvature of the corners of the bottom sections and being provided with flanges on the bottom and sides. The No. 60 packing is also used between the flanges, as shown at 34 in Figs. 5 and 6. The upper edges of all side and side-corner sections have overhanging or rolled edges, such as shown at 54, 51, and 58, to provide additional strength. After the corner sections have been bolted in place, the side sections 55 and 56, having drilled flanges along their bottom and side edges, may

then be bolted to the corner sections 51 and 52 and to the bottom sections, the above-mentioned Johns-Manville packing being used between the flanges. The complete pool, therefore, is thus assembled.

The above design of the swimming pool is such that it may be easily and quickly dismantled and assembled by a minimum number of men, such as two, and is durable and rugged enough to stand rough treatment. Since the tank sections are of sheet aluminum, such as 61S-W, the bottom is sufficiently flexible to conform to an uneven surface, thus permitting the pool to be erected on rough ground. It is realized that the sections of the pool may be made in various sizes, and when large sized pools are constructed, the side members, such as 56, could be supported by outrigger bracing, such as shown at 62 and 62' in Fig. 4. The size of the bottom sections may be 10 in the neighborhood of 5 x 10 feet and the side sections, 5 x 12 feet. In order to facilitate erection and to prevent the loss of bolts, the bolts 36 15 may be welded to strips, thereby permitting as many as twelve bolts to be positioned with the 20 same motion. All iron and braces are galvanized 25 to avoid any rust and possible electrolytic action between the aluminum and other metals.

Another feature of the tank is the provision of a scum or over-flow gutter, such as is shown at 30 63 in Fig. 3. This gutter may be suspended and adjustable on a strip 64 hung over the rolled edge 58 of the upper end corner and side members. The gutter may have an inclination toward 35 one corner and a drain provided which will pass out through flexible tubing through a hole in the side of the tank. The hand rail 18 encircles the deck and may be arranged to be easily set on the post studs 10 and fastened firmly in place 40 in any suitable manner. The ladders may be simply hooked onto the deck members. Furthermore, in the circulatory filter system, a heater 45 may be added, if desired, in order to provide the desired temperature.

I claim:

45 1. A rectangular pool construction comprising a plurality of bottom members each having an upturned end at right angles to the horizontal plane of said members, a plurality of corner-bottom members each having an upturned end and an upturned side, and a plurality of side members, said bottom and corner members along one side of said pool having interlocking stepped-back edges adjacent one another and right angle flanges along the upper edges of said upturned ends and sides, and said side members having bottom right angle flanges adapted to overlap the stepped back edges of said bottom members and to be fastened to said flanges on said upturned ends and sides, and said side members having 50 right angle side flanges adapted to fasten said side members to each other, one corner of each of said bottom and corner-bottom members having a double stepped-back configuration to form 55 a triple overlapping joint with the corners of the three contacting bottom members.

2. A rectangular swimming pool construction comprising a plurality of sheet sections adapted to be attached to form a tank, said sections including a first plurality of similar bottom sections 70 having horizontal portions and right angle, vertical portions, said sections having stepped-back edges on at least two edges of each section, a flange along the upper edges thereof and a double stepped-back corner, a pair of corner-bottom sections having horizontal portions and right angle

vertical portions, said sections having stepped-back bottom edges, flanges along the upper edges thereof, and a double stepped-back corner, said first plurality of bottom sections and said corner-bottom sections forming one-half of the bottom of said tank, a second plurality of similar bottom sections having horizontal portions and right angle vertical portions, said sections having a stepped-back edge along one side thereof, a second pair of corner-bottom sections having horizontal portions and right angle vertical portions, said sections having a stepped-back edge along one side thereof, said second plurality of bottom sections and said second pair of said corner-bottom sections forming the other half of the bottom of said tank, four of said sections overlapping at the double stepped-back corners to form a water-tight joint thereat, a plurality of vertical side sections having flanges along the side and bottom edges thereof and extending over the jointure between bottom sections, and corner-side sections having flanges along the side and bottom edges thereof, all of said flanges being adapted to be attached to adjacent flanges to form said tank.

3. A rectangular swimming pool construction comprising a plurality of sections adapted to be assembled to form a tank, said sections including flat bottom sections having upturned ends with fastening flanges thereon, said bottom sections including corner-bottom sections, certain of said corner-bottom sections having stepped-back edges along two edges thereof, the intersection of said two edges forming a double stepped-back corner, and certain of said other bottom sections having stepped-back edges along two sides thereof, the intersection of said two edges forming a double stepped-back corner, said other bottom sections having a stepped-back edge on one side thereof, the other side of said sections overlapping the stepped-back edges of said other sections, four of said sections overlapping at the double stepped-back corners to form a water-tight joint thereat.

4. A swimming pool construction comprising a plurality of pre-formed bottom sections adapted to be assembled to form a leak-proof tank, said sections having upturned ends with fastening flanges thereon, four corner-bottom sections having upturned ends and upturned sides with fastening flanges thereon, said four corner sections and said bottom sections having stepped-back edges adapted to overlap and be fastened together to form a bottom unit, the contact corners of four of said sections having a double

stepped-back configuration to permit overlapping of said four sections at said corners and a plurality of vertical side sections with fastening flanges along the bottom and vertical edges thereof, said side sections overlapping the jointure between said bottom sections and including four corner sections adapted to be fastened to the corner sections of said bottom unit, and means adapted to be inserted between said fastening flanges and between overlapping edges of said bottom sections for making said tank leak-proof.

5. A swimming pool construction, comprising a plurality of sections adapted to be assembled to form a tank, said sections including flat, bottom sections having upturned ends and sides, certain of said bottom sections having stepped-back edges along two edges thereof, the intersecting corner of said two edges forming a double stepped-back corner, and certain of said other bottom sections having a stepped-back edge along one edge thereof, the intersection of the end of said one stepped-back edge and the intersection of said two stepped-back edges forming a double stepped-back corner, four of said sections overlapping at the double stepped-back corner to form a water-tight joint thereat and along the overlapping edges of said sections.

6. A swimming pool construction in accordance with claim 5, in which said bottom sections have flanges along the upper edges thereof and a plurality of side sections having bottom flanges for attachment to said bottom member flanges and side flanges for attachment to each other, said side sections extending over the jointure between said bottom sections.
